Albert Claude Della Porta, Leicester, England

Application February 18, 1948, Serial No. 144,565
In Great Britain June 12, 1945

Term of patent 7 years

(Cl. D56—1)

To all whom it may concern:

Be it known that I, Albert Claude Della Porta, a subject of the King of Great Britain, residing at 41 Shanklin Drive, Leicester, England, have invented a new, original, and ornamental Design for a Drum Bracket, of which the following is a specification, reference being had to the accompanying drawings, forming part thereof.

Figure 1 is a perspective view of a drum bracket, said view showing my new design.

Figure 2 is a side elevation.

Figure 3 is an end elevation.

Figure 4 is a plan and

Figure 5 is an underneath plan of the drum bracket.

I claim:

The ornamental design for a drum bracket, substantially as shown.

ALBERT CLAUDE DELLA PORTA.
